UNITED STATES PATENT OFFICE.

ANNIE BAYLIS, OF BUFFALO, NEW YORK.

DESIGN FOR A GAME-BOARD.

SPECIFICATION forming part of Design No. 32,377, dated March 20, 1900.

Application filed January 4, 1900. Serial No. 396. Term of patent 3½ years.

To all whom it may concern:

Be it known that I, ANNIE BAYLIS, a citizen of the United States, residing at Buffalo, in the county of Erie and State of New York, have invented and produced a new and original Design for a Game-Board, of which the following is a specification.

The accompanying drawing, forming part of this specification, represents a plan view of my design for a game-board with a background which represents an American flag.

As shown in the drawing, the leading or material features of my design consist of a circular saucepan-body 2, provided with an annular rim 3 and with a laterally-projecting handle 4, provided at its outer end with the usual suspension-opening 5. Arranged upon the annular flange or rim 3 are a plurality of

symbols 9, representing a varied multiplicity of animals, and arranged upon the peripheral portion of the pan-body is a circular series of plus and minus characters 11.

Having fully described my invention, I claim as new and desire to secure by Letters Patent—

The design for a game-board, substantially as herein shown and described.

In testimony that I claim the foregoing as my invention I have signed my name, in presence of the subscribing witnesses, this 30th day of December, 1899.

ANNIE BAYLIS.
